UNITED STATES PATENT OFFICE.

GEORGE G. WELSH, OF BIGSPRING, TEXAS.

CATTLE-GUARD.

SPECIFICATION forming part of Letters Patent No. 729,465, dated May 26, 1903.

Application filed February 5, 1903. Serial No. 142,019. (No model.)

To all whom it may concern:

Be it known that I, GEORGE G. WELSH, a citizen of the United States, residing at Big-spring, in the county of Howard and State of Texas, have invented new and useful Improvements in Cattle-Guards, of which the following is a specification.

My invention relates to cattle-guards; and the object of the same is to construct a simple and efficient device of this character which will be effective for preventing cattle from straying from a wagon-road into the inclosures along railroad-tracks.

The simple and novel construction used by me in carrying out my invention is fully described in this specification and claimed, and illustrated in the accompanying drawings, forming a part thereof, in which—

Figure 1 is a plan view of my device. Fig. 2 is a transverse section of the same on the line 2 2, Fig. 1. Fig. 3 is a detail of one of the disks. Fig. 4 is an elevation of a modified star-shaped form of disk I may use instead of the circular disks.

Like numerals of reference designate like parts in the different views of the drawings.

My device is located on a railroad-track comprising two rails 1, secured to sills 2, substituted for the usual cross-ties at a point where the track intersects a fence and makes a break therein. Rectangular frames 3 are secured to the sills 2 intermediate the rails 1 and comprise sides 5 and ends 6, having apertured flanges 5^a and 6^a, respectively, formed thereon. Rectangular frames 7 are secured to the sills 2 outside of the track and in alignment with the frames 3. The frames 7 comprise sides 8 and ends 9, which have apertured flanges 8^a and 9^a, respectively, formed thereon. Shafts 10 and 11 are journaled in bearings formed on the sides 5 and 8, respectively, and mounted to revolve on the shafts 10 and 11 are a series of blunt-edged disks 12, which are loosely mounted thereon and are held against movement longitudinally of

the shafts by means of sleeve 13, which leave the disks 12 free to slightly wabble, since the central apertures in the disks are rounded off on the edges. The disks 12 are located to break the intervals.

By the construction just described cattle are prevented from going through the break in the fence or the disks 12 will wabble and turn under their feet and prevent their securing a foothold thereon.

I do not wish to be limited as to details of construction, as these may be modified in many particulars without departing from the spirit of my invention.

A star-shaped disk 14 is shown in Fig. 4, which may be employed instead of the circular disk.

Having described my invention, what I claim as new, and desire to secure by Letters Patent, is—

1. In a cattle-guard a cylindrical shaft, a series of disks having central apertures therein rounded out on their edges to permit said disks to wabble and to rotate on said shaft, and sleeves mounted on said shaft intermediate said disks, with small intervening spaces between the ends thereof and the disks, substantially as described.

2. In a cattle-guard, the combination of a cylindrical shaft, a series of disks beveled from the center to a blunt edge and having apertures therein loosely fitting said shaft thereby permitting said disks to wabble, and sleeves mounted intermediate said disks, with small intervening spaces between the ends of said sleeves and said disks, substantially as described.

In testimony whereof I have hereunto set my hand in presence of two subscribing witnesses.

GEORGE G. WELSH.
